COMBINED VACUUM CLEANER AND UTILITY CART

Warren H. Nobles, Commodore Hotel, 79 N. Western, and William C. La Chapelle, 712 Cherokee Ave., both of St. Paul, Minn.

Filed June 10, 1959, Ser. No. 56,305

Term of patent 14 years

(Cl. D14—3)

FIG. 1

FIG. 4

Figure 3 is a front perspective view with the cord in a stored position and with the hose and attachment omitted for convenience of illustration; and

The dominant features of our new design reside in the portions shown in full lines.

We claim:

The ornamental design for a combined vacuum cleaner and utility cart, as shown and described.
